UNITED STATES PATENT OFFICE.

MICHAEL KUNKEL, OF GRAND RAPIDS, MICHIGAN.

BOX CLAMP.

1,426,394.

Specification of Letters Patent. Patented Aug. 22, 1922.

Application filed April 1, 1921. Serial No. 457,579.

To all whom it may concern:

Be it known that I, MICHAEL KUNKEL, a citizen of the United States, residing at Grand Rapids, in the county of Kent and State of Michigan, have invented certain new and useful Improvements in Box Clamps, of which the following is a specification.

My invention relates to improvements in clamps, or clasps for securing small match boxes in place upon the match containing part of the box, and its objects are: first, to provide a means whereby it will be impossible for the box to become removed from the container; second, to provide a means for so protecting the box and container that matches cannot escape from the container without the direct efforts of the user of the matches, and, third, to provide a means for so securing the matches that may be used indefinitely upon different boxes of the same size.

I attain these objects by the construction shown in the accompanying drawing, in which Fig. 1 is a perspective of a match box with my appliance in place upon it. Fig. 2 is an end view of the same, and, Fig. 3 is a perspective of my appliance removed from the box.

Similar reference characters indicate similar parts throughout the several views.

In forming this device, or implement the wire is first bent at *a* to form the arms 3 and 4, and then it is bent at *b* and *c* to form the loops 2 and made integral by welding the ends of the wire together, which loops are to be of such size as to fit closely all around the box.

It will be noticed that with this formation the parallel arms 3 are each independent of the other, and I find it well and, in fact, necessary to have the arms 4 slightly depressed at the free ends so the arms 3 will press downwardly, or inwardly upon the cover of the box, as indicated in Fig. 2, as by this means the edges of the box will be pressed below the edges of the container and thus form a locking means that will prevent the container, designated as 1', from being moved endwise in the box until the arms 3 have been properly adjusted to allow the end of the box to pass over the end of the container.

This implement may be made with a di-

vided wire, but I greatly prefer the electrically welded ends of the wire, as by this means the loops and the parallel arms are made, practically, of one endless piece of wire, rendering it much stronger, less liable to get out of condition, and much more reliable in its action, both in its construction and in its application upon a box.

It will be readily understood that, though I have limited my description and use to the securing of a match box, there are many places where the implement, or its close mechanical equivalent may be used, hence I do not desire to restrict myself to any particular use for the implement, but reserve all rights to the invention in its broadest sense.

I desire, especially, to call the attention of the public to the fact that, under the peculiar construction of this device it may be readily sprung open for passing it over, or upon the object to be secured, its natural resiliency will cause it to closely clasp the object after it has been properly placed, especially by reason of the arms 4 being depressed as they approach the arms 3.

Having thus fully described my invention, what I claim as new in the art, is:

1. In an implement for securing a match box cover upon the match container, two parallel arms bent oppositely at right angles at each end and then bent to form a continuous rectangular loop at each end of the implement of a proper size to exactly fit around the box and cover.

2. In an implement for securing a match box cover upon the match container, two parallel arms bent oppositely at right angles, each arm movable independently of the other, the right angled ends of the arms bent to form a right angled loop at each end of, and at right angles with the parallel arms.

3. In an implement for securing a match box cover upon the match container, an endless wire bent to form two parallel arms with a right angular loop at each end of the arms and at right angles therewith.

4. In an implement of the kind named, an endless wire formed with two parallel arms bent oppositely at right angles at each end, thence bent to form two parallel loops, one at each end of the arms and at right angles therewith, and the arms depressed toward the opposite side of the loops.

5. In an implement of the kind named, an

endless wire forming two parallel arms, each end of the parallel arms bent in opposite directions at right angles with the parallel arms, thence each right angled arm bent 5 at right angles with itself and with the parallel arms, thence bent to form connecting cross bars, thus forming a rectangular loop

at each end of the parallel arms, the arms and the loops being integral and each parallel arm movable independently of the other. 10

Signed at Grand Rapids, Michigan, March 24, 1921.

MICHAEL KUNKEL.
